UNITED STATES PATENT OFFICE.

GEORGE P. WIGGINTON, OF KALAMAZOO, MICHIGAN, ASSIGNOR TO KALAMAZOO LOOSE LEAF BINDER CO., OF KALAMAZOO, MICHIGAN.

BINDER DEVICE

1,267,830.

Specification of Letters Patent. Patented May 28, 1918.

Application filed February 5, 1917. Serial No. 146,762.

To all whom it may concern:

Be it known that I, GEORGE P. WIGGINTON, a citizen of the United States, residing at Kalamazoo, county of Kalamazoo, State of Michigan, have invented certain new and useful Improvements in Binder Devices, of which the following is a specification.

This invention relates to improvements in binder devices.

10 The main objects of this invention are:

First, to provide an improved binder device which facilitates the handling or manipulation of loose sheets such as are used for accounting purposes.

15 Second, to provide an improved device which facilitates the handling and manipulation of temporary binders or loose sheet holders.

Further objects, and objects relating to 20 structural details, will definitely appear from the detailed description to follow.

I accomplish the objects of my invention by the devices and means described in the following specification. The invention is 25 clearly defined and pointed out in the claims.

A structure which is a preferred embodiment of my invention is clearly illustrated in the accompanying drawing, forming a part of this specification, in which:

30 Figure I is a perspective view of a structure embodying the features of my invention.

Fig. II is a longitudinal section of the structure adjusted to one of its positions 35 with the binder arranged therein, parts of the binder being broken away.

Fig. III is a vertical longitudinal section with the parts adjusted to another position.

Fig. III^A is a detail vertical longitudinal 40 section through one of the binding strip slots.

Fig. IV is a side elevation with the binder in its closed position.

Fig. V is a vertical longitudinal section 45 similar to that of Fig. III, showing another type of binder adjusted to the device.

Fig. VI is a side elevation showing another adjustment of the device with the binder shown in Fig. V arranged therein.

50 Fig. VII is an enlarged detail section on a line corresponding to line 7—7 of Figs. II and V, illustrating details of the spring detent or locating stop for the guide member.

Fig. VIII is a perspective view of another embodiment of my invention in which only 65 one of the side members is adjustable, a follower being mounted upon the end member.

Fig. IX is a side view of the embodiment 60 of Fig. VIII with a binder of the post type arranged therein.

Fig. X is a vertical longitudinal section of the embodiment shown in Figs. VIII and IX, adjusted to another position.

Fig. XI is a side elevation with the follower adjusted to operative position and a 65 binder arranged in the device.

Fig. XII is a vertical longitudinal section showing the binder illustrated in Fig. XI in its closed or locked position.

Fig. XIII is an enlarged detail section on 70 a line corresponding to line 13—13 of Fig. XI, showing details of the mounting for the follower.

Fig. XIV is a detail section on a line corresponding to line 14—14 of Fig. XIII. 75

Fig. XV is a detail plan view of one of the binder members shown in Figs. XI and XII.

Fig. XVI is a detail section on a line corresponding to line 16—16 of Fig. XV. 80

In the drawing similar reference characters refer to similar parts throughout the several views, and the sectional views are taken looking in the direction of the little arrows at the ends of the section lines. 85

Referring to the drawing, the binder shown in Figs. II, III and IV comprises the covers 1 and clamping members 2, separably associated or constituting separably associated binder members. The posts 3 are removable, the clamping members 2 being provided with sockets 4 adapted to receive the same. The binding strips 5 extend between the clamping members and suitable mechanism is provided within the covers for adjusting the same, the binder shown in these figures being that of my Patent No. 1,174,458, dated March 7, 1916. 90

The binder shown in Figs. V, VI, IX and X is of the post type and comprises a pair 100 of covers 6 to which the clamping members 7 are pivotally connected, the post 8 being adjustably secured to each of the clamping members by a suitable means, the details of which are not illustrated, as they form no 105 part of this invention.

The binder shown in Figs. XI and XII comprises a pair of binder members 9. One of the binder members is provided with a spring clutch 11 adapted to engage the post 12. The sheets 13 are suitably perforated to receive the post and are also notched at their inner edges to receive the binding strips 5 and engage the sheet guide member, as will be hereinafter described.

10 The embodiment illustrated in Figs. I to VII, inclusive, is especially designed for supporting a binder and sheets, but may be used for supporting sheets without a binder, comprises a pair of base members 14 connected by cross pieces 15. The side members 16 are secured to the cross members 15 by means of the hinges 16' so that they may be swung to the erected position, as shown in Figs. I and II, or one of them collapsed, 20 as shown in Fig. III, or both collapsed, as shown in Fig. VI.

25 The end member 17 is disposed between the side members to coact therewith in providing a U-shaped holder when both of the side members are erected, as shown in Fig. II, or to provide a pair of holders, as shown in Fig. III, or as in Fig. VI, so that one binder member may be arranged in each holder. The end member is supported for 30 vertical as well as tilting adjustment. To accomplish this, it is provided with a pair of downwardly projecting plates 18 having vertical slots 19 therein, the slots having opposed seats 20 intermediate their ends. These slots are adapted to coact with the 35 pivots 21 arranged on the inner sides of the base members 14 so that the end member is guided in its vertical and tilting adjustment and will tilt the same in either direction.

40 To automatically adjust the end member with the adjustable side members, the side members are provided with inwardly projecting arms 22 which project under the end member to elevate it or tilt it and support it in its elevated or tilted positions. When 45 one of the side members only is collapsed, the end member is supported in an inclined relation to the other end member, preferably at right angles thereto, as shown in Fig. III. When both of the guide members are collapsed, as shown in Fig. VI, the end member is raised and supported upon the arms of both side members.

50 The end member is provided with a sheet guide 23, which is mounted in a slide-way 55 24 upon the end member, the slide-way being open at its ends so that the guide may be removed or introduced by longitudinal movement.

To locate the guide centrally, I provide a 60 stop 25 which is supported yieldingly by the coil spring 26 so as to engage a socket 27 in the under side of the guide. The ends of the guides are so positioned that they serve as rests for the binder clamping mem-

bers when a binder is arranged in the support, as shown in Fig. II, or as shown in Fig. III. The device may be quickly adjusted to support the binder member in the desired relation to permit the manipulation of the sheets back and forth from one position to the other when the device is adjusted to its U-form, as shown in Fig. II, or permit the adjustment of the device to the position, as shown in Figs. III or VI, or the adjustment of the sheet from one binder member 75 to the other.

To close the binder, the device is adjusted with one of the side members collapsed and the other erected. This brings the end member to a position at right angles to the erected side member, which facilitates the alining of the sheet so as to receive the post 3. The guide 23 serves to aline the sheets with their slots 28 in position to receive the binding strips 5. The guide member is then 80 removed which permits the other binder member being adjusted to position, as shown in Fig. IV, so that the binder may be locked up as desired.

To accommodate the binding strips, the 90 end member 17 is provided with transverse slots 29 into which the binding strips drop when the binding strips are extended and the binder arranged, for example, as in Fig. III.

95 In the embodiment shown in Figs. I to VI, the side members are supported in their erected position by the bail-like supports 30 which are pivoted on the inner sides of the base members 14. The cross portions 31 of the supports 30 are engaged in slots 32 of the keepers 34. These keepers have offsets 35 at their lower ends adapted to receive the supports when the side members are erected. Springs 36 are mounted on the side members to engage the cross portions of the support when the parts are brought to their erected position and hold them yieldingly in the notches of the keepers.

100 When it is desired to collapse the side members, the supports are pulled outwardly to disengage them from the notches of the keepers and then slid out in the slot as the sides are collapsed.

110 In Figs. VIII to XII I show another embodiment of my invention in which but one of the side members is made adjustable. In this embodiment the side member 37 is mounted upon the base members 38 in a fixed relation, the base member being provided with an upright portion 39 adapted to support the side member 37. The coacting side member 40 is hinged at 41 to the base members while the end member 42 is hinged at 43 to the lower end of the side member 37. The side member 40 is provided with arms 44 which project under the end member 42 to actuate the same. The adjustable side member 40 may be adjusted 115 120 125

to an erected position to coact with the side member 37 and the end member 42 to provide a U-shaped holder or may be collapsed as shown in Fig. X to provide a pair of 5 holders. The side member 40 is supported in erected position by means of links 45 and 46 which are pivotally connected to each other at 47, the link 46 being connected to the side member at 48, while the link 45 is connected to the base at 49. A stop 50 is provided to limit the movement of the links and support them in their erected or extended position. When the side member 40 is collapsed a pair of binder member holders is 10 provided, the same as shown in Fig. III. This embodiment of my invention is quite satisfactory for various purposes and uses.

The end member 42 is provided with a 15 guide member 51 corresponding to the guide members 23. To vary the capacity of the holder, I provide a follower 52 which may be adjusted against the side member 37, as shown in Fig. IX or to an intermediate position, as shown in Fig. XIII. This follower is provided with arms 53 which project down at the sides of the end member and is provided with shoes 54 which ride against the under side of the end members so that the follower is supported in an 20 adjusted position. The follower has holes 55 alined with holes 56 in the side member 37 to receive the posts 12 when adjusted as shown in Fig. XII. The follower may be 25 shown in the embodiment of my invention 30 shown in Figs. I to VI but I have not shown it in that connection as I deemed the illustration of Fig. VIII sufficient.

My improved binder device is especially 35 desirable in so-called "Machine Accounting" although it is advantageous for use in the keeping of records by hand. By its use binders and sheets are supported so that their manipulation is very greatly facilitated.

I have illustrated and described my improvement as I have embodied the same in practice. I have not attempted to illustrate 40 or describe certain embodiments which I contemplate as I believe the disclosure made 45 will enable those skilled in the art to which my invention relates to embody or adapt the same as the desired uses or operating conditions may render desirable.

In my copending application, Ser. No. 55 146,106, filed Feb. 2, 1917, I claim broadly certain features disclosed herein.

Having thus described my invention what I claim as new and desire to secure by Letters Patent, is:

60 1. In a device of the class described, the combination of a pair of base members and connecting cross pieces therefor, of a pair of side members hinged upon said cross members to be adjusted to rest upon said base

members or to a raised position, an end member disposed between said side members, plates mounted centrally on said end member to project downwardly at the inner sides of said base members and having slots therein with opposed pivot seats intermediate the 65 ends of the slots, pivots on said base members engaging said slots, arms mounted on said side members to support said end member in an elevated position when both are collapsed and inclined toward the erected side 70 member when one side member is erected and the other collapsed and to permit it to rest on said base members in a horizontal position between said side members when both are erected, and supports for said side 75 members.

2. In a device of the class described, the combination of side members mounted for pivotal adjustment, an end member disposed between said side members for adjustment, a downwardly projecting centrally disposed plate on said end member having a slot therein with opposed intermediate pivot seats, a pivot engaging said slot and coacting with said plate to 80 guide said end member in its adjustment, and arms mounted on said side members to support said end member in an elevated position when both are collapsed and inclined toward the erected side member when one 85 is erected and the other collapsed and to permit it to rest in a horizontal position between them when both are erected.

3. In a device of the class described, the combination of pivotally mounted side members, an end member disposed between said side members for adjustment, a centrally disposed guide member for said end member permitting it to be raised or tilted in either direction, and arms mounted on said side 100 members to support said end member in a raised position when both are collapsed and inclined toward the erected side member when one is erected and the other collapsed 105 and to permit it to rest in a horizontal position between them when both are erected.

4. In a device of the class described, the combination of side members pivotally mounted for adjustment, an end member mounted between said side members for tilting and vertical adjustment, and operating connections for said side and end members whereby said end member is supported in an elevated position when both side members are collapsed and inclined toward the erected 115 side member when one is erected and the other collapsed and permitted to rest in a horizontal position between said side members when both are erected.

5. In a device of the class described, the 120 combination of side members mounted for adjustment, an end member adjustably mounted between said side members to coact

therewith, and operating connections for said side and end members whereby said end member is adjusted to an inclined relation to the erected side member when one is erected and the other collapsed and permitted to rest in a horizontal position between said side members when both are erected.

6. In a device of the class described, the combination of side members mounted for independent adjustment, an end member mounted between said side members for tilting adjustment relative to said side members so that said end member may be adjusted to an inclined relation toward the erected side member when one is erected and the other collapsed and permitted to rest in a horizontal position between said side members when both are erected.

7. In a device of the class described, the combination of side members mounted for pivotal adjustment, a coacting end member adjustably mounted between said side members, and operating connections between said side and said end members whereby when said side members are erected a U-shaped holder is provided and when one is collapsed and the other erected said end member is supported in an inclined position to coact with the erected side member.

8. In a device of the class described, the combination of side members pivotally mounted at their lower ends, a coacting end member mounted between said side members for tilting adjustment, and arms on said side members engaging said end member to sup-

port it in an inclined relation to the other side member when one of said side members is collapsed.

9. In a device of the class described, the combination of adjustably mounted side members, and a coacting adjustably mounted end member operatively associated with said side members so that when said side members are erected a U-shaped holder is provided and when one is collapsed the end member is supported in an inclined position to coact with the erected side member.

10. In a structure of the class described, comprising an end member and coacting side member, a guide member mounted on said end member, said guide member being removably supported in a slideway on said end member so that it may be removed and introduced by a longitudinal movement, and a spring locating stop for said guide mem- 55

11. In a structure of the class described, the combination of a pair of side members and coacting end member disposed to provide a U-shaped holder, a guide member removably mounted on said end member adapt- 60 ed to be engaged and disengaged by a lon- gitudinal movement.

In witness whereof I have hereunto set my hand and seal in the presence of two wit- 65 nesses.

GEORGE P. WIGGINTON, [L. s.]
